(57) **CLAIM**

The ornamental design for a case for electronic device with multi-angle stand cover, as shown and described.

DESCRIPTION

FIG. 1 is a front perspective view of a case for electronic device with multi-angle stand cover shown in a first open position;

FIG. 2 is a front elevation view of the FIG. 1 device in the first open position;

FIG. 3 is a rear elevation view of the FIG. 1 device in the first open position;

FIG. 4 is a right-side elevation view of the FIG. 1 device in the first open position;

FIG. 5 is a left-side elevation view of the FIG. 1 device in the first open position;

FIG. 6 is a top plan view of the FIG. 1 device in the first open position;

FIG. 7 is a bottom plan view of the FIG. 1 device in the first open position;

FIG. 8 is a rear perspective view of the FIG. 1 device in the first open position;

FIG. 9 is a front perspective view of the FIG. 1 device shown in the closed position;

FIG. 10 is a front perspective view of the FIG. 1 device in a second open position;

FIG. 11 is a right-side view of the FIG. 1 device shown in the second open position; and

FIG. 12 is a front perspective view of the FIG. 1 device in a third open position; and,

FIG. 13 is a right-side elevation view of the FIG. 1 device shown in the third open position.

The broken lines represent portions of the structure and an environment of use that forms no part of the claim.
